(57) CLAIM

The ornamental design for a head bandana, as shown and described.

DESCRIPTION

FIG. 1 is a front view of a head bandana showing my new design.

FIG. 2 is a back view of the head bandana.

FIG. 3 is an end edge view of the head bandana.

FIG. 4 is a top edge view of the head bandana; and,

FIG. 5 is a bottom edge view of the head bandana.

The fragmented crosshatch pattern shown on the bandana represents fabric and is repeated throughout the areas shown.
